UNITED STATES PATENT OFFICE.

CARL F. BUSCHNER, OF NEW YORK, N. Y.

DESIGN FOR FRINGE.

SPECIFICATION forming part of Design No. 28,621, dated May 10, 1898.

Application filed March 25, 1898. Serial No. 675,189. Term of patent 7 years.

To all whom it may concern:

Be it known that I, CARL F. BUSCHNER, a citizen of the United States, residing at New York city, county and State of New York, have invented and produced a new and original Design for Fringe, of which the following is a specification, reference being had to the accompanying drawings, forming part thereof.

Figure 1 represents a perspective view of my newly-designed fringe. Fig. 2 is a cross-section, and Fig. 3 an upper edge view thereof.

The leading feature of my design consists of a fringe having a double upper edge composed of two rows of loops, a head beneath such edge, and a brush beneath the head.

The letters *a a'* represent the double upper edge of the fringe composed of two rows placed side by side. Each row is formed of a series of elongated loops that meet on diametrically opposite corners. Below the double upper edge *a a'* there is formed the twilled head *b*, and beneath the head *b* is formed the brush *c*.

What I claim is—

The design for fringe, substantially as herein shown and described.

CARL F. BUSCHNER.
